Primary Examiner — Samantha Wood(74) *Attorney, Agent, or Firm* — Honigman LLP; Eric J. Sosenko; Jonathan P. O'Brien(57) **CLAIM**

The ornamental design for a wash basin, as shown and described.

DESCRIPTION

FIG. 1 is a perspective view of a wash basin showing the new design;

FIG. 2 is another perspective view of the wash basin seen in FIG. 1;

FIG. 3 is a front elevational of the wash basin seen in FIG. 1;

FIG. 4 is a rear elevational view of the wash basin seen in FIG. 1;

FIG. 5 is a left side elevational view of the wash basin seen in FIG. 1;

FIG. 6 is a right side elevational view of the wash basin seen in FIG. 1;

FIG. 7 is a top plan view of the wash basin seen in FIG. 1; and,

FIG. 8 is a bottom plan view of the wash basin seen in FIG. 1.

In the drawings, the dashed lines depict portions of the wash basin that form no part of the claimed design. The dash-dot lines in the drawings define the bounds of the claimed design and form no part thereof.

1 Claim, 5 Drawing Sheets(56)
